LAPPING MACHINE

Herbert S. Indge and George E. Hulbert, Westboro, Mass., assignors to Norton Company, Worcester, Mass., a corporation of Massachusetts

Application October 9, 1944, Serial No. 557,753

6 Claims. (Cl. 51—119)

1

This invention relates to abrading machines, and more particularly to a lapping machine for lapping a plane face of relatively small work pieces.

One object of the invention is to provide a simple and thoroughly practical lapping machine for lapping a plane face on a work piece. Another object of the invention is to provide a lapping machine for lapping a plane face on a work piece, in which each work piece is independently rotated while maintained in operative engagement with a rotary gyrating lapping element. Another object of the invention is to provide a lapping machine with a work driving head having a plurality of rotatable work driving spindles which are arranged so that they may be independently moved to engage and drive a work piece for a lapping operation.

A further object of the invention is to provide a lapping machine with a work driving mechanism including a plurality of positively rotated work driving spindles each of which may be independently moved to and from an operative position to facilitate loading and unloading work pieces. A further object of the invention is to provide a lapping machine with a work driving head having a plurality of positively driven work rotating and driving spindles, in which the head is arranged so that it may be indexed to facilitate loading and unloading work pieces. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

One embodiment of this invention has been illustrated in the accompanying drawings in which like reference numerals indicate like parts.

Fig. 1 is a side elevation of the improved lapping machine having parts broken away and shown in section to clarify the operating mechanisms of the machine;

Fig. 2 is a fragmentary vertical sectional view, on an enlarged scale, through the work rotating and driving mechanism and the lapping wheel; and

Fig. 3 is a fragmentary detail view of the latch mechanism for holding the work driving head against rotation during the normal lapping operation.

A lapping machine has been illustrated in the drawings comprising a base 10 which serves as a

2

support for a rotatable lap supporting platen 11 and a work head 12. The lap supporting platen 11 is fixedly supported on a rotatable spider 13 which is keyed to the upper end of a sleeve 14. The sleeve 14 is rotatably journalled in a bearing 16 adjacent to its lower end which is in turn supported in a housing 17. The housing 17 is fixedly mounted on the base 10. The upper end of the sleeve 14 is journalled in a bearing 18 which is fixedly supported on the upper end of the housing 17.

A driving mechanism is provided for the lap supporting platen 11 comprising an electric motor 20 which is mounted within the base 10 of the machine on an adjustable pivotally mounted motor support 21. The motor 20 is provided with a driving pulley 22 which is connected by means of a driving belt 23 with a pulley 24. The pulley 24 is mounted on a rotatable shaft 25. The shaft 25 is provided with a worm 26 which in turn meshes with a worm gear 27. The worm gear 27 is keyed to the lower end of the sleeve 14. It will be readily apparent from the foregoing disclosure that rotary motion of the motor 20 is transmitted through the mechanism above described to rotate the sleeve 14, the spider 13, and the lap supporting platen 11.

A lapping plate 30 is provided which rests upon the upper surface of the platen 11. In order to produce a predetermined lapping action, the lapping plate 30 is preferably not only rotated but also is given a combined rotary and gyrating movement to impart the desired lapping action to the work pieces being lapped. A plurality of symmetrically arranged driving pins 31 and 32 (preferably three in number, only two of which have been illustrated in Figs. 1 and 2) are provided to engage apertures in the lapping plate 30. The driving pins or studs 31 and 32 are eccentrically mounted on rotatable heads 33 and 34, respectively, in a manner substantially the same as that shown in the expired U. S. patent to H. S. Indge No. 1,610,527 dated December 14, 1926, to which reference may be had for details of disclosure not contained herein. The heads 33 and 34 are rotatably supported on studs 35 (only one of which has been illustrated in Fig. 1). The rotary heads 33 and 34 are provided with gears 36 and 37 which mesh with a gear 38. The gear 38 is keyed to the upper end of a non-rotatable shaft 39. The shaft 39 is contained within a hollow aperture in the sleeve 14 and is supported at its lower end by means of a bracket 39 which is fixed relative to the housing 17. The gears 36 and 37 also mesh with an annular internal ring

50 55

gear 49 which is fixedly supported relative to the spider 13. As the spider 13 is rotated by the driving mechanism above described, the ring gear 40 will impart a rotary motion to the gears 36 and 37 to revolve the eccentric driving studs 31 and 32. During this driving movement, the gears 36 and 37 roll on the stationary center gear 38. The lapping plate 30 will be given a rotary motion due to rotation of the lap supporting platen 11 and the heads 33 and 34, and at the same time will be given a gyrating motion by means of the revolving driving studs 31 and 32.

The work pieces to be lapped are preferably independently rotated while in engagement with the rotary and gyrating lapping plate 30. The machine base 10 is provided with an upwardly extending column 45 which serves as a support for an arm 46. The arm 46 is provided with a vertically extending cylindrical aperture 47 which serves as a bearing support for a vertically movable sleeve 48. The sleeve 48 supports a normally-stationary rotatably-mounted work driving head 49 at its lower end. The head 49 is rotatably supported by a pair of roller bearings 50 and 51 on the lower end of the sleeve 48. The head 49 serves as a support for a plurality of symmetrically arranged work driving and rotating spindles 52, 53, 54, 55, 56, 57, 58, 59 and 60. Each of the spindles 52 to 60 inclusive is preferably provided with a driving member of a flexible or yieldable material, such as a flexible soft rubber cup 61 which may be held in frictional engagement with a work piece to be lapped by means of a compression spring 62. The work driving spindle 52 is supported in spaced anti-friction bearings 63 and 64 which are in turn fixedly mounted in the head 49. The spindle 60 is similarly supported in anti-friction bearings 65 and 66. The remaining spindles are similarly supported, consequently the details of construction of each spindle have not been illustrated in the drawings.

A suitable driving mechanism is provided simultaneously to rotate all the work driving spindles 52-60 inclusive. This mechanism may comprise an electric motor 70 which is mounted on the rear end of the arm 46. The motor 70 is provided with an armature shaft 71 having a multiple V-groove stepped driving pulley 72 mounted thereon. A driving V-belt 73 connects the pulley 72 with a multi-V-groove stepped pulley 74 which is keyed to the upper end of a vertically extending shaft 75. The pulley 74 is preferably supported by anti-friction bearings 76 and 77 which are fixedly supported within a bracket 78. The bracket 78 is fixedly mounted relative to the arm 46 so as to form a rigid support for the driven pulley 74 to prevent the thrust of the driving shaft from being wholly taken up by the shaft 75.

The shaft 75 passes through a central aperture 79 formed within the sleeve 48 and is rotatably journaled in bearings 80 and 81 which are carried by the sleeve 48. The lower end of the shaft 75 is journaled in a thrust bearing 82 which is supported by the head 49. A gear 83 is keyed to the lower end of the shaft 75 and meshes with a gear 84 which is supported on a rotatable shaft 85. The shaft 85 also supports a gear 86 which meshes with a gear 87. The gear 87 is keyed to a rotatable sleeve 88 which serves as a support for the work rotating and driving spindle 52. A drive is provided between the sleeve 88 and the spindle 52 comprising a driving pin 89 which is fixed to the spindle 52. The driving pin

89 extends through an elongated slot 89a formed in the upper end of the sleeve 88.

A similar driving connection is provided between each of the spindles 52 to 60 inclusive (see, for example, spindle 60).

The sleeve 88 is provided with a driving gear 90 which meshes with a large diameter gear 91. The gear 91 is rotatably supported by anti-friction bearings 92 on the sleeve 48. Each of the work rotating and driving spindles 53, 54, 55, 56, 57, 58, 59 and 60 is provided with a driven gear 93 which meshes with the large gear 91. These gears 93 are formed integral with the driving sleeves 94 (only one of which has been illustrated in detail in connection with work driving spindle 60). It will be readily apparent from the foregoing disclosure that rotary motion of the shaft 75 will be transmitted through the gear 83, the gear 84, the gear 86, the gear 87, the driving sleeve 88, and the gear 90, to rotate the large gear 91. The large gear 91 meshes with the gear 93 on each of the remaining work driving and rotating spindles 53 to 60 inclusive and will transmit an independent rotary motion to each of the driving spindles to frictionally rotate a work piece in operative engagement with the rotary and gyrating lapping plate 30 so as to impart the desired lapping action to a plane face on the work piece.

Each of the friction driving members 61 mounted on the lower ends of the work driving and rotating spindles 52 to 60 inclusive is arranged so that it may be moved upwardly to facilitate removal of a finish lapped work piece and the insertion of a new piece of work to be lapped. Each of the spindles 52-60 inclusive is provided with knurled knobs 95, 96, 97, 98, 99, 100, 101, 102 and 103, respectively. The knob for the spindle 56 is not shown as it is directly behind the sleeve 48 in Fig. 2.

When it is desired to remove a finish lapped work piece, the operator may manually raise any one of the knobs 95-103 inclusive so as to raise the frictional driving member 61 from driving engagement with the work piece being lapped, after which the work piece may be removed and a new work piece inserted in place underneath the driving member 61. The spindles 52 to 60 inclusive are raised a sufficient distance so that the driving pins 89 are raised out of the slots 89a, thus disconnecting the spindles so that rotation thereof is stopped during a loading operation. The compression of the spring 62 is sufficient to maintain the driving member 61 in frictional driving relation with the work piece to be lapped and also to produce the desired lapping pressure between the work piece and the rotary gyrating lapping wheel 30.

In order to facilitate loading and unloading of work pieces, the head 49 is rotatably supported, in the manner above described, on the sleeve 48. The head 49 is provided with a plurality of radially projecting lugs 105, 106 and 107 (only three of which have been illustrated in Fig. 1). A spring actuated latch 108 is arranged in the path of the lugs 105, 106 and 107 (Figs. 1 and 3). The latch or pawl 108 is pivotally supported on a stud 109 which is in turn supported by a pivotally mounted arm 110. The arm 110 is pivotally supported on a stud 111 which is arranged so that the arm 110 together with the pawl 108 may be swung upwardly out of the path of the lugs 105, 106 or 107. The arm 110 is provided with a stop surface 112 which is arranged when in an operative position to engage a stop surface 113 which is fixedly mounted on the column 45 so as to support the

pawl 108 in an operative position. A tension spring 114 is provided normally to maintain the pawl 108 in an operative position. When it is desired to allow the work head 49 to rotate to facilitate loading or unloading of work pieces, the pawl 108 is raised out of engagement with the lug 105, after which the rotary thrust of the driving mechanism above described will cause the head 49 to rotate. The pawl 108 is immediately dropped into position after this rotary motion has started so that it will engage the next lug on the housing 49. Or, if desired, the pawl may be held out of the path of the lugs 105, 106 or 107 so that the head may be rotated through 90°, 180° or more, as desired.

In order to facilitate raising the head 49 to an inoperative position, the sleeve 48 is provided with rack teeth 115 which mesh with a rotatable pinion 116 which may be actuated by a hand wheel (not shown) to raise the entire work drive head 49 to an inoperative position. A manually-operable pivotally-mounted holding pawl 117 is provided having gear teeth formed therein which mesh with the teeth on the rack bar 15 so that the sleeve 48 may be held in the desired adjusted position.

In order precisely to locate the head 49 in an operative position, a positive stop mechanism may be provided comprising a bracket 120 which is fixed relative to the arm 46 having an upper plane surface which serves as a positive stop. A bracket 121 is fixedly mounted relative to the head 49. A stop rod 122 is fixedly connected to the bracket 121 and is provided at its upper end with a stop collar 123 which is screw threaded onto the threaded end portion 124 of the rod 122. A lock collar 125 is provided to lock the collar 123 in adjusted position.

The operation of this improved lapping machine will be readily apparent from the foregoing disclosure. The lapping machine is set in motion by starting the electric motors 20 and 70. The starting of the electric motor 20 serves in the manner above described to impart a combined rotary and gyrating movement to the lapping plate 36. The starting of the electric motor 70 serves to transmit a rotary motion to all the work rotating and driving spindles. In order to load work pieces in the machine, the knobs 95-103 inclusive are independently raised and a work piece inserted in position under the driving member 61, after which the knob is released and the released compression of the spring 62 will serve to maintain the driving element 61 in frictional driving engagement with the work piece to be lapped to rotate the work piece in operative contact with the rotary and gyrating lapping plate 36. The lapping operation on the work pieces is continued to the desired and predetermined extent. When it is desired to remove a work piece from the machine, it is merely necessary for the operator to raise one of the knobs 95-103 inclusive to withdraw the frictional driving element 61 from driving engagement with the work piece, after which the lapped work piece may be readily removed from the machine and a new work piece inserted there instead.

After the spindles adjacent to the operator's station have been loaded with work pieces, the latch or pawl 108 may be raised out of engagement with the lug 105 so as to allow the head 49 to rotate to bring other work spindles into position adjacent to the operator's station. As above described, the head 49 may be rotated through either 90°, 180° or 270°, depending on the opera-

tor holding the pawl 108 out of engagement therewith until the head 49 has reached the desired position.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

15 We claim:

1. In a lapping machine having a base, a lapping wheel having a plane operative lapping face, means to impart a combined rotating and gyrating movement to said wheel, a vertically adjustable hollow spindle, a work head including a plurality of positively rotated work driving spindles which is rotatably supported at the lower end of said hollow spindle, a spindle driving mechanism including a drive shaft rotatably supported within said hollow spindle, gearing within said head connecting said drive shaft with each of said spindles simultaneously to rotate said spindles, a yieldable frictional work driving member on each of said spindles, and independent yieldable means normally to maintain said spindles in frictional driving engagement with a work piece to rotate the same while in lapping engagement with said lapping wheel at a predetermined pressure.

2. In a lapping machine having a base, a lapping wheel having a plane operative lapping face, means to impart a combined rotating and gyrating movement to said wheel, a vertically adjustable hollow spindle, a work head including a plurality of positively rotated work driving spindles which is rotatably supported at the lower end of said hollow spindle, a spindle driving mechanism including a drive shaft rotatably supported within said hollow spindle, gearing within said head connecting said drive shaft with each of said spindles simultaneously to rotate said spindles, the thrust of said drive gearing normally tending to rotate said work head, a plurality of stop lugs on said head, and a stop pawl normally to hold said head against rotation, said stop pawl being pivotally mounted to facilitate indexing the work head for loading and unloading work pieces.

3. In a lapping machine having a base, a lapping wheel having a plane operative lapping face, means to impart a combined rotating and gyrating movement to said lapping wheel, a vertically adjustable hollow spindle, a work head rotatably mounted on the lower end of said spindle, a plurality of hollow driving sleeves rotatably supported on said head and having their axes parallel to said hollow spindle, a drive shaft rotatably supported in said spindle, gearing within said work head connecting said drive shaft with each of said driving sleeves positively to rotate said sleeves, a work driving spindle slidably mounted in each of said sleeves, a yieldable frictional work driving member on each of said spindles, a compression spring normally to maintain said member in frictional driving engagement with the work piece to maintain it in operative lapping engagement with said lapping wheel at a predetermined pressure, a driving pin on each of said spindles normally engaging a slot in each of said sleeves to drive said spindles, and a manually operable means including a knob rotatably mounted on the upper end of each of said spindles to facilitate

moving said spindles independently to an inoperative position to facilitate loading and unloading work pieces.

4. In a lapping machine having a base, a lapping wheel having a plane operative lapping face, means to impart a combined rotating and gyrating movement to said wheel, a vertically adjustable hollow spindle, a work head including a plurality of positively rotated hollow work driving sleeves which is rotatably supported at the lower end of said hollow spindle, a sleeve driving mechanism including a drive shaft rotatably supported within said hollow spindle, gearing within said head connecting said drive shaft with each of said sleeves continuously to rotate all of said sleeves, an axially movable work driving spindle within each of said hollow sleeves, a work driving member on each of said work drive spindles, a driving pin connecting each of said spindles with said sleeves, and independent manually operable means to raise each of said work drive spindles to disconnect it from its driving sleeve when it is desired to remove a finish lapped work piece.

5. In a lapping machine having a base, a lapping wheel having a plane operative lapping face, means to impart a combined rotating and gyrating movement to said wheel, a vertically adjustable hollow spindle, a work head including a plurality of positively rotated hollow work driving sleeves which is rotatably supported at the lower end of said hollow spindle, a sleeve driving mechanism including a drive shaft rotatably supported within said hollow spindle, gearing within said head connecting said drive shaft with each of said

sleeves continuously to rotate all of said sleeves, an axially movable work drive spindle within each of said sleeves, a work driving member on each of said work drive spindles, a driving pin on each of said work drive spindles which is engageable with a slot in each of said hollow sleeves, and independent manually operable means to disengage said drive pin to stop said work drive spindle to facilitate removal of the finish lapped work piece.

6. In a lapping machine having a base, a lapping wheel having a plane operative lapping face, means to impart a combined rotating and gyrating movement to said lapping wheel, a vertically adjustable hollow spindle, a work head including a plurality of positively rotated work driving spindles which is rotatably supported at the lower end of said hollow spindle, a spindle driving mechanism within said head including a drive shaft rotatably supported within said hollow spindle, gearing within said head operatively connecting said shaft with all of said spindles positively and simultaneously to rotate all of said spindles, a yieldable friction work driving member on each of said spindles, independent yieldable means normally to maintain each of said driving members in frictional driving engagement with the work piece to rotate the same while in lapping engagement with the lapping wheel at a predetermined pressure, and independent manually operable means to withdraw said spindles to an inoperative position to facilitate loading and unloading work pieces.

HERBERT S. INDGE.

GEORGE E. HULBERT.
